UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

DOUBLE MULTICOLOR WEB PERFECTING ROTARY PRINTING PRESS

Application filed April 16, 1930. Serial No. 444,747.

This invention comprises a double multicolor web perfecting rotary printing press in which the first and second printing units are arranged at right angles to each other, 5 with the provision of an interposed web turning device.

This invention further comprises a printing press of the above character in which the printing units are located in the same horizontal plane so that the corresponding inking mechanisms of both printing units will 10 be subjected to the same temperature for ensuring the proper distribution and laying of the inks.

15 This invention further comprises a press of the above character in which the plate cylinders of different printing units are disposed around their impression cylinder at one side of its horizontal central plane.

20 This invention further comprises a press of the above character in which the plate cylinders of each printing unit are disposed around the upper side of their impression cylinder so that the web may be located under the inking mechanisms for said plate 25 cylinders, thereby causing all web paper dust to drop away from rather than into the inking mechanisms. This arrangement of the plate cylinders also permits a downward 30 pressure at all times on the impression cylinder shaft bearings.

A practical embodiment of my invention is represented in the accompanying drawings, in which

35 Fig. 1 represents diagrammatically a top plan view of the press with the inking mechanisms removed;

40 Fig. 2 represents diagrammatically a view of the press with the first printing unit shown in side elevation and the second printing unit in end elevation; and

45 Fig. 3 represents diagrammatically a detail view showing the second printing unit in side elevation.

50 In the first printing unit of the press the impression cylinder is denoted by 1 and its plate cylinders by 2, 3, 4, 5, which plate cylinders are shown as arranged around the upper side of the impression cylinder.

55 These plate cylinders are provided with inking mechanisms 6, 7, 8, 9 of any well known or approved form.

In the second printing unit of the press the impression cylinder is denoted by 10 and its plate cylinders by 11, 12, 13, 14, 55 which plate cylinders are arranged around the upper side of the impression cylinder. These plate cylinders are provided with inking mechanisms 15, 16, 17, 18, of any well known or approved form.

60 The two printing units are arranged in substantially the same horizontal plane so that the corresponding inking mechanisms of the two printing units will be subjected to the same temperature for facilitating the 65 distribution and laying of the inks.

The two printing units are arranged at substantially right angles to each other and a web turning device 19 is placed between the two printing units, to change the direction 70 of travel of the web after it has left the first printing unit.

The web 20 to be printed in multicolor on both sides is shown as passing from its supply roll 21 over a roll 22 and under a 75 roll 23 to and around the upper side of the impression cylinder 1 of the first printing unit under the plate cylinders 2, 3, 4, 5. From thence the web printed in multicolor on one side is fed under the roll 24 to and 80 around the web turning device 19 and from thence under a roll 25 to and around the upper side of the impression cylinder 10 of the second printing unit under the plate cylinders 11, 12, 13, 14. From thence the web 85 printed in multicolor on both sides is led under a roll 26 and through a cutting mechanism, such, for instance, as a pair of coacting rotary cutters 27, 28.

An offset web 29 is shown as being fed 90 from its supply roll 30 to and around the impression cylinder 10 of the second printing unit and from thence to its take-up roll 31.

The two printing units of the press may 95 be driven from a common source of power, such, for instance, as an electric motor 32 which is herein shown as having a pulley and a belt drive connection 33, 34, 35, with a cross shaft 36 connected through a train 100

of gears 37, 38, 39, 40 with the impression cylinder of the first printing unit and through the bevel gears 41, 42, shaft 43 and train of gears 44, 45, 46, 47 with the impression cylinder 10 of the second printing unit.

From the above description it will be seen that by placing the two printing units in the same horizontal plane and by locating the plate cylinders of the two printing units around the upper sides of their respective impression cylinders a number of advantageous results are obtained. As hereinabove set forth, this arrangement permits the use of two similar printing units with corresponding members in the same horizontal plane. It also permits the web to be located under the inking mechanisms of the two printing units so that all paper dust will drop away from rather than into the inking mechanisms. It will also permit the corresponding inking mechanisms of the two printing units to be subjected to the same temperature, to facilitate the distributing and laying of the inks. This arrangement also ensures a downward pressure at all times on the impression cylinder shaft bearings.

It is evident that various changes may be resorted to in the construction, form and arrangement of the several parts without departing from the spirit and scope of my invention, and hence I do not intend to be limited to the particular embodiment herein shown and described, but

What I claim is:—

1. In a double multicolor web perfecting rotary printing press, first and second multicolor printing units located at substantially right angles to each other, and a web turning device located between the printing units, each printing unit comprising an impression cylinder and a plurality of plate cylinders arranged around the impression cylinder at one side of its horizontal central plane.

2. In a double multicolor web perfecting rotary printing press, first and second multicolor printing units located in practically the same horizontal plane and at substantially right angles to each other, and a web turning device located between the printing units, each printing unit comprising an impression cylinder and a plurality of plate cylinders arranged around the impression cylinder at one side of its horizontal central plane.

3. In a double multicolor web perfecting rotary printing press, first and second multicolor printing units located at substantially right angles to each other, and a web turning device located between the printing units, each printing unit comprising an impression cylinder and a plurality of plate

cylinders arranged around the upper side of the impression cylinder.

4. In a double multicolor web perfecting rotary printing press, first and second multicolor printing units located in practically the same horizontal plane and at substantially right angles to each other, and a web turning device located between the printing units, each printing unit comprising an impression cylinder and a plurality of plate cylinders arranged around the upper side of the impression cylinder.

In testimony, that I claim the foregoing as my invention, I have signed my name this 11th day of April, 1930.

HOWARD M. BARBER.
